UNITED STATES PATENT OFFICE.

MARTIN WILLIAM MOORE, OF SPRINGFIELD, ILLINOIS

ACETYLENE-GAS LAMP.

1,070,352.

Specification of Letters Patent. Patented Aug. 12, 1913.

Application filed May 6, 1912. Serial No. 695,469.

To all whom it may concern:

Be it known that I, MARTIN WILLIAM MOORE, a citizen of the United States, residing at Springfield, in the county of Sangamon and State of Illinois, have invented 5 certain new and useful Improvements in Acetylene-Gas Lamps; and I do declare the following to be a full, clear, and exact description of the invention, such as will enable others skilled in the art to which it 10 pertains to make and use the same.

This invention relates to improvements in acetylene gas lamps.

One object of the invention is to provide 15 a lamp of this character which is particularly adapted for the use of miners and which is provided with an improved construction and arrangement of feeding mechanism whereby the water from the reservoir of the lamp is controlled and discharged into the generating chamber in the desired quantities.

With this and other objects in view, the invention consists of certain novel features 20 of construction, and the combination and arrangement of parts as will be more fully described and claimed.

In the accompanying drawings; Figure 1 is a central vertical sectional view of my im- 25 proved lamp; Fig. 2 is a horizontal sectional view thereof, taken on the line 2—2 of Fig. 1; Fig. 3 is a detail perspective view of the supporting plate for the perforated water distributing cup of the lamp.

30 My improved lamp comprises a base section 1 which contains the carbid and forms the gas generating chamber of the lamp. The base section 1 is threaded exteriorly at its upper end and onto said threaded portion is screwed a gas chamber 2 which is in the form of an inverted cap and has its sides bent outwardly to form a radially disposed annular recess 3. The lower end of the cap 2 forming the gas chamber is threaded 35 interiorly as at 4 and is adapted to be screwed down onto the threaded upper end of the base section 1. In the annular recess 3 of the chamber 2 and engaged with the upper edge of the base section 1 is a gasket 5 and between the gasket and the upper wall of the recess 3 is clamped the outer edge of a gas filtering screen 6 which extends across 40 and covers the lower end of the chamber 2 as shown. The gasket 5 forms a gas tight 45 connection between the chamber 2 and the

upper end of the generating chamber formed by the base 1.

Secured to and having a fluid tight engagement with the sides of the cap forming the chamber 2 is a water reservoir 7 in the upper end of which is arranged a filling opening 8, normally closed by a screw plug 9 as shown. Secured to one side of the lower portion of the water reservoir 7 is a reflector 10 and arranged through the lower portion of the reflector and through the adjacent sides of the reservoir 7 and gas chamber 2 is a gas discharging tube 11 in the outer end of which is secured a burner 12.

Arranged in the bottom of the base section or generating chamber 1 of the lamp is a cup supporting plate 13 having thereon a centrally disposed upwardly projecting circular boss 14 which is preferably struck up from the plate 13 as shown. Engaged but detachably connected with the boss 14 on the plate 13 is a perforated water distributing cup 15 which projects upwardly to a suitable distance in the generating chamber. Arranged in the center of the reservoir 7 80 and extending downwardly through the cap 2 forming the gas chamber and having its lower end projecting into the water distributing cup to a point near the lower end thereof is a water conducting tube 16 in the lower end of which is formed a tapered valve seat 17. In the tube 16 adjacent to the bottom of the reservoir 7 or upper side of the cap 2 are water discharging passages 18 of which there may be any suitable number 90 and through which the water from the reservoir 7 discharges into the tube 6.

The upper end of the tube 16 is closed and has therein a threaded passage 19 with which is engaged the threaded upper end of a valve stem 20 which is disposed in the tube 16 and has on its lower end a conical shaped valve 21 which is adapted to be engaged with the seat 17 in the lower end of the tube whereby the latter is opened and closed to permit the discharge of water from the tube into the distributing cup 15. The water when thus discharged into the distributing cup 15 passes through the discharge openings therein onto the carbid in the lower portion of the generating chamber. The water in discharging through the apertures in the cup 15 will be evenly distributed onto the carbid and by providing the valve 21 as herein shown and described 110

the discharge of water may be readily controlled. Any suitable means may be employed for operating the valve, said means being here shown as a crank handle 22 which is engaged with or secured to the projecting upper end of the valve stem 20, whereby the latter may be turned in one direction or the other and thus screwed upwardly or downwardly in the threaded passage 19 in the upper end of the tube 16 thus raising or lowering the valve into and out of operative engagement with its seat.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described my invention, what I claim is:

An acetylene gas lamp comprising upper and lower sections adapted to be detachably and hermetically connected, the lower section having exterior threads formed thereon, a water conducting tube carried by the upper section rigidly secured to the top of the same and depending therefrom, a valve

stem screwed within the closed upper secured end of said tube and provided with an enlarged conical shaped lower end for adjustable engagement with the lower detached correspondingly shaped end of the tube, whereby the water through the latter is controlled, a perforated tubular water distributing cup detachably supported in an upright position upon the base of the lower section, said cup surrounding the lower disconnected open end of the tube and projecting a suitable distance above the same, an inverted cap secured between said sections, said cap having its sides bent outwardly to form a circumferentially disposed annular recess, the lower end of said cap being screw threaded interiorly and adapted to be screwed upon exterior screw threads on the upper end of the base section, a filtering screen and gasket secured between the sections within the cap forming a gas chamber, and a burner tube communicating with the latter and in communication with the inverted cap.

In testimony whereof I have hereunto set my hand in presence of two subscribing witnesses.

MARTIN WILLIAM MOORE.
